Primary Examiner — Nicole C Shiflet*Assistant Examiner* — Danielle Nichole Bowly*(74) Attorney, Agent, or Firm* — Venable LLP(57) **CLAIM**

The ornamental design for a printer, as shown and described.

DESCRIPTION

FIG. 1 is a front view of a printer showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

The dash-dotted broken lines define the bounds of the claimed design; the evenly spaced broken lines show portions of the printer; all broken lines form no part of the claimed design.

1 Claim, 5 Drawing Sheets(56)
